CLAIM

The ornamental design for a cover for remote controller or the like, as shown and described.

DESCRIPTION

FIG. 1 is a front, top, and left side perspective view of a cover for remote controller or the like, showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, bottom, and left side perspective view thereof; and,

FIG. 9 is a back, top, and left side perspective view thereof.

1 Claim, 4 Drawing Sheets
